UNITED STATES PATENT OFFICE.

JOHN B. HADAWAY, OF SWAMPSMOTT, MASSACHUSETTS, ASSIGNOR TO UNITED SHOE MACHINERY CORPORATION, OF PATERSON, NEW JERSEY, A CORPORATION OF NEW JERSEY.

MACHINE FOR OPERATING ON SHOE PARTS.

Application filed May 19, 1924. Serial No. 714,398.

This invention relates to machines for operating on blanks and particularly to machines for treating shoe parts. Although the invention, in its broader aspects, is applicable to the handling of blanks in general, the invention is herein shown by way of exemplification as embodied in a machine designed for treating unattached heels, to finish the breast surfaces of the heels by first trimming them to a predetermined shape and then scouring the breast surfaces.

Certain shoe parts of a similar shape, which are to be treated in large quantities, may conveniently be handled by conveyors, the parts being positioned on the conveyors and presented to a succession of tools and then automatically ejected. Such a machine is especially adapted, for example, for finishing the breast surfaces of unattached composite heels, each composed of a leather base and a rubber top lift, which are constructed as described in United States Letters Patent No. 1,613,096, granted January 4, 1927, upon my application. A heel of the type therein described comprises an outer cushion of rubber and a base of leather or other suitable material, the two portions being arranged for exact and expeditious assemblage by the aid of coacting protuberances and cavities upon the contacting surfaces of the two portions. Preferably the protuberances will be formed upon the leather heel base and the cavities in the rubber portion, and in addition the heel seat face will be provided with jig holes to assist in the proper location of the heel upon a carrier.

With a view to facilitating operating on blanks such as heels of the type referred to, one object of the present invention is to provide an improved machine of the type having a conveyor, which machine will be organized to present such blanks to a plurality of operating tools in succession and particularly adapted for the expeditious location of the blanks upon the conveyor, and the automatic clamping, treatment, unclamping and ejection of the blanks.

The expeditious positioning of blanks, such as the composite heels described in my above-mentioned application, may be secured in a manner already known, by the provision of jig pins upon the conveyors, for example endless carriers, which are adapted to enter the jig holes in the heels. As is common in machines of this type, clamping devices may be provided to hold the blanks after they have been positioned, and preferably these clamping devices are arranged automatically to be moved into clamping position and released therefrom by means operable by the rotation of a turret upon which the carriers are mounted. When jig pins are provided upon a work carrier to enter jig holes in the blank, as before indicated, the blanks, after the clamp upon the carrier has been released, may cling to the jig pins. In this aspect, one feature of the invention relates to an ejecting device whereby the blanks may be separated from the jig pins and to another ejecting device operable by movement with respect to a fixed cam, said latter ejecting device being arranged to push the blank out of the clamping device. Preferably the arrangement will be such that the clamping device, the ejector for lifting the blank off the jig pins, and the ejector for pushing the blank laterally out of the clamping device will be operated in timed relation to one another.

The conveyor in such a machine may conveniently take the form of an annular turret similar to that described in Letters Patent of the United States No. 1,514,615, granted November 11, 1924, upon my co-pending application, with a plurality of rotatable tools mounted upon axes substantially perpendicular to the plane of rotation of the turret, or parallel to the axis of rotation of the turret, inside the annulus. Where one of these tools is a scouring tool and provided with a surface of abrasive material, the tool diameter may become reduced in use and the tool may become ineffective where the path of movement with respect to the tool is maintained constant even though

the remaining abrasive material is capable of still further use. Accordingly, still another feature of the invention relates to means for adjusting the center of rotation of the turret with respect to the tools so that the path of movement of the work is changed, the wearing away of the tool is compensated for, and its effect upon successive pieces of work kept substantially constant.

In accordance with still other features of the invention, the preferred embodiment herein shown and described provides a driving motor for the turret whose axis is substantially parallel to the axis of rotation of the turret, said motor being connected to the turret by a novel arrangement which is so arranged that the driving connections are not disturbed by the adjustment of the center of rotation of the turret as above described. These driving connections are also constructed to cause the turret to move through predetermined fractions of a rotation and then to dwell for a predetermined period intermediate between each of said fractional movements. Preferably the driving connections between the source of power and the scouring tool are such that axial movement is imparted to said tool as well as rotating movement so as to distribute the wear of the work across the width of the periphery of the tool. This preferred embodiment of the invention is described in the accompanying specification and shown in the drawings, in which:—

Fig. 1 is a front elevation of the machine;

Fig. 2 is a side elevation with parts broken away;

Fig. 3 is a plan view;

Fig. 4 is a detail section showing a controlling cam; and

Fig. 5 is a radial section through the turret taken at the center of one of the clamping devices.

The illustrated machine is a motor driven machine provided with an annular turret upon which are mounted several work carriers provided with clamping devices. A plurality of tools, such as a rotary trimming tool and a rotary scouring tool, are located within the annulus in position to treat a portion of the periphery of the heels, such as the breast surfaces, as they are presented to these tools during rotation of the turret.

Each of the carriers is slidably mounted upon the turret for movement radially thereof under the control of stationary cams to determine the relative path of traverse of the tools and the heels and each of them has a supporting surface provided with jig pins by means of which the leather base of the composite heel may be located accurately by an inexperienced operator. If the heel is of the type described in my above-mentioned Letters Patent No. 1,613,096, then the rub-

ber section may also be located expeditiously by the use of the coacting protuberances and cavities upon the contacting surfaces thereof. The turret is rotated intermittently by novel connecting means between the driving motor and the turret, which latter is arranged to carry a heel from the position at which it was inserted in the work carrier to a position beyond the rotary trimming tool and then to dwell. As the carrier left the starting position and approached the trimming tool, the clamping device was automatically brought into contact with the rubber section of the heel and will be maintained in contact until various operations have been finished and the heel is ready to be ejected. After this dwell, the turret is again rotated for a fractional movement and carries the heel past the rotary scouring tool which is also reciprocated vertically along its axis. Another dwell is then provided which permits the operator to insert a fresh piece of work in the carrier which has come opposite his position, after which the particular heel under consideration is moved forward, its clamp is released, and ejecting device lifts the heel off the jig pins and then another ejecting device slides it laterally out of the clamping device, which latter is then ready to receive a new piece of work when it approaches the operator's position.

The base of the machine is in the form of a substantially rectangular hollow standard 10 provided at one side with an opening 12 (Fig. 2) adapted normally to be closed by means of a door 14. Within the standard 10 is a bracket 16 supporting an electric motor 18 which is connected by means of an Oldham coupling 20 to a vertical shaft 22 on the upper end of which is removably secured a heel breast trimming cutter 24 (Fig. 3). The motor 18 may conveniently be controlled by means of a switch 30 (Fig. 1) mounted on the exterior of the casing at the front of the machine. Adjacent to this switch 30 is another switch 32 for controlling an electric motor 34 which is fastened to the base of the machine within the casing 10. A vertical shaft of this motor is also connected by means of an Oldham coupling 36 (Fig. 1) to a vertical shaft 38 through a sliding connection 40 (Fig. 2), thus allowing both rotation around a vertical axis of the upper portion of the shaft and reciprocation along said axis. Mounted on the upper end of the shaft 38 is a scouring wheel 42 (Fig. 3) having a peripheral face considerably wider than the thickness of the heel to be scoured.

For economy of operation it is desirable to utilize all portions of the peripheral surface of this scouring wheel and I have, therefore, provided a mechanism for reciprocating the shaft 38, which carries the scouring wheel, back and forth along its axis so that

various portions of the vertical peripheral surface of the scouring tool are presented to the work. This mechanism may be best seen in Fig. 2. It will be seen to comprise a 5 curved lever 44 pivoted at 46 on a bracket 48 attached to the frame of the machine. The lever 44 has an outer forked end provided with rolls engaging an annular groove 50 formed on the lower end of the worm 52 which is pinned to the upper portion of the 10 shaft 38. This worm 52 is arranged for engagement with a gear 54 rotatably mounted on a stub shaft fixed in the frame of the machine. Eccentrically attached at 56 to 15 the hub of this worm gear 54 is a link 58 which is connected at its lower end to the central portion of the curved lever 44. As the worm 52 is rotated by the motor it will 20 rotate the worm gear 54 and thereby cause an oscillation of the lever 44 which will move the worm and its shaft 38 up and down at the same time that it is being rotated, thus giving the desired movement to the 25 scouring wheel 42.

The upper part of the casing 10 is provided with transverse horizontal guideways 60 (Fig. 1) in which there is slidably mounted a turret-carrying slide 62 connected by means of an overhanging bracket 30 64 (Fig. 2) to a hand wheel 66 having a threaded connection 68 with the frame of the machine so that the slide 62 and all parts supported thereby may be given a slight adjusting movement transversely of 35 the top of the casing. As will later appear, this movement is for the purpose of bringing the work up to the scouring wheel 42 as the wheel wears away by adjusting the center of rotation of the turret to change the 40 relation of the path of movement of the work with respect to the tool. The effective diameter of the wheel 42 may become reduced by the wearing away of the abrasive cover or by reason of a matting down or 45 wearing away of the felt or other resilient backing material. Because of the relative location of the rotary trimming cutter 24, spaced about 120 degrees from the scouring wheel, as will appear from an inspection of 50 Fig. 3, adjustment of this slide and its associated parts will not affect to any considerable extent the relation of the work and the heel dressing knife.

For supporting the turret, there is bolted 55 to the slide 62 an annular ring 69 (Fig. 2) which supports an annular block 70 having a cam track 72 formed in its peripheral face. A conveyor in the form of a rotating annular turret 74 is formed near its inner edge 60 with a depending sleeve 75 (Figs. 2 and 3) which passes through the opening in the cam block 70 and has a ring gear 98 (Fig. 3) secured to its lower end. The weight of 65 the rotating parts is borne by ball bearings 77 in a race 79 between the ring gear and

the slide 62. A central cover plate 81 held in place on a bracket 91 by the screw 93 is used to keep chips and dust away from the driving mechanism.

The turret 74 serves as a support for a 70 plurality of work-holding devices, herein-after described, or carriers. In the illustrated machine there are three sets of work-holding devices or carriers and the machine is organized to rotate the turret through 120 75 degrees and then to cause the same to dwell, whereupon the turret will proceed through another arc of 120 degrees to bring each piece of work past its respective tool. The dwells of the turret and carriers occur when 80 no work is being done by the tools upon the heels and permit insertion of a heel in one of the carriers while it is at rest. This movement of the turret is effected by means of the arrangement of its driving gears, as 85 illustrated in Figs. 2 and 3, from which it will be seen that a horizontal shaft 80 (Fig. 2) is mounted in bearings in the frame of the machine. The shaft is driven by means of a worm 82 upon the motor shaft 90 38 meshing with a gear 84 (Fig. 3) fixed to the horizontal shaft 80. Slidably mounted along a spline on this horizontal shaft is a worm 86 (Fig. 2) formed at one end with an annular groove 88 (Fig. 3) and 90 meshing on its face with a worm gear 90 (Fig. 2) mounted on a vertical jack shaft 92. Intermediate between the upper and lower parts of the jack shaft 92 is an Oldham coupling 94 and on the upper end of the 100 shaft is a spur gear 96 (Fig. 3) meshing with the ring gear 98 which is operatively connected to the turret to cause rotation thereof.

To provide for the desired dwells in the 105 turret rotation, a bell crank lever 100 (Fig. 2) is pivoted at 102 in a bracket 104 formed on the frame of the machine and this lever is bifurcated at its other end and provided with blocks 106 engaging the annular groove 110 88 in the end of the worm 86. Pivots attached to the bell crank lever 100 at an intermediate point 110 is an arm 112 (Fig. 3) carrying a roller 114 arranged to ride in a groove 116 of a cam 118 (Fig. 2) fixed 115 to the jack shaft 92. It will be seen that rotation of the jack shaft through the interposed worms and gears will cause the cam to oscillate the bell crank lever 100 and thereby to slide the worm 86 along the horizontal shaft 80 so that at intervals its rotative effect upon the gear 90 will be neutralized and the turret 74 will remain stationary.

For the purpose of holding the work, the 125 turret is provided at spaced intervals with carriers comprising plates 120 (Fig. 1) which are slidably mounted in radial grooves 122 formed in the surface of the turret, said plates being retained in the grooves by means 130

of screw-attached removable retaining members 124 (Fig. 2). Springs 126 supported in lugs 128 formed on the lower side of the turret are arranged to bear against depending members 130 formed on the lower side of the slidable plates and these members are provided with rollers 132 adapted to bear against the upper part of the peripheral face of the cam block 70. This block 70 may 10 be provided with inset cam members 134 (Fig. 4) adjacent to the two operating tools and the surface of the inset cam members 134 may be so designed as to cause or allow a radial movement of the work-supporting 15 plates 120 under the action of the springs 126. By this arrangement, any variation between the curvature of the breast of the heel and the curvature of the turret will be compensated for and the proper action of 20 the tools along this curved breast surface of the work properly carried out.

Inasmuch as the breast surface of the heel may not be exactly perpendicular to the tread surface thereof the upper face of each 25 supporting plate 120 will usually be provided with a sloping projection 140 (Fig. 2) which has on its upper surface jig pins 142 adapted to coact with the corresponding 30 jig holes in the heel seat surface of a heel to enable the operator readily to locate the heel on this member 140 and to predetermine the 35 position for the subsequent treatment of the heel. This construction not only ensures that the heel will be located in a definite position with relation to the clamp, so that the heel breast may be given a definite treatment by relative movement between the 40 clamp and the treating tools, but also ensures against accidental movement of the heel between the clamping members in a plane parallel to the tread face while it is being treated. After the operator has placed the rubber section 210 of the heel securely on the top of the leather section 246 thereof, 45 and located the parts in superposed relation or approximate register, the heel will be suitably clamped against the projection 140 by means of a clamping plate 144 (Fig. 1) 50 slidably mounted on upstanding pins 146 which are held by brackets formed on each sliding plate 120.

Slidably secured in the upper surface of the turret 74 are studs 150 (Fig. 2) serving as supports for sleeves 152 slidably mounted 55 on reduced portions of said studs and provided with offset arms 154 (Fig. 1) having rollers 156 (Fig. 2) at their outer end. These rollers are arranged for engagement beneath overhanging ledges 160 on the 60 clamping plates 144 and vertical movement of the sleeves will be thereby communicated to the clamping plates 144 to clamp the work against the projecting members 140 and later to unclamp the work in order to 65 release the same at the desired time. The

sleeves 152 are resiliently secured on the shouldered studs 150 by means of stiff springs 168 interposed between the upper edges of the sleeves and adjusting nuts 166 threaded on the reduced upper ends of the 70 studs 150 and these sleeves 152 and their arms 154 normally move with said studs. The studs 150 extend through the turret and are slidably mounted in suitable bearings therein. The lower ends 162 of the 75 studs 150 are provided with rollers 164 adapted to engage the cam track 72 so as positively to actuate the clamping members both to clamp and unclamp the work.

From an inspection of Fig. 2 it will be 80 observed that the cam track 72 is provided with an elevated portion adjacent to the front of the machine so that as the corresponding work clamp approaches the front of the machine, the rod 162 will be pushed 85 upward and the clamping plate 144 thereby released. On the other hand, as the particular clamp which is at the front of the machine leaves this position the rod 162 will be pulled down to cause the clamping plate 90 95 144 firmly to contact with the tread surface of the heel under a predetermined spring pressure which may be adjusted by turning the nut 166.

After the heel has been operated upon by 95 the rotating cutter 24 and the scouring wheel 42, it is desired that it shall be automatically ejected in order to leave the work clamp empty for the insertion of a fresh piece of work. To this end an elevating means comprising three rods 170 is slidably mounted in each of the base portions 140 and the rods are connected at their lower ends to plates 172 provided with depending arms 173 each having a roller 175 (Fig. 5) to coact with a 100 projection upstanding from the stationary block 70 so that as the work is unclamped by the upward movement of the roller 164 in the cam slot 72, these rods 170 will be 105 elevated and serve forcibly to raise the work above the jig pins 142. Ejection of the work from the holder is then effected by means of an arm 180 mounted on the upper end of a short shaft 182 pivoted in the turret adjacent to each work holder and said shaft 110 has clamped to its lower end a lever 184 provided at its outer end 186 with a roll engaging a cam track 188 (Fig. 3) formed in a portion of the slide 62. This cam track is 115 shown in dotted lines in Fig. 3 and it will be observed that its shape is such that a resilient portion 190 attached to the outer end of each of the arms 180 is forcibly moved between the clamp members to eject the heel after it has been unclamped and as soon as 120 it has been lifted from the jig pins by the rods 170. A similar pair of ejectors is provided for each of the clamps but, because of the circular form of the larger portion of the cam track 188 and the level surface of 125 130

the majority of the block 70, they remain idle until the work has been operated upon by the tools 24 and 42 and is approaching the re-loading station.

- 5 From the above description it will be seen that the operator will stand at the front of the machine adjacent to the hand wheel 36 and supply work to the open clamping device in front of him and adjust the wheel 66
- 10 as the occasion may require. Because of the provision of the Oldham coupling 94 the slight amount of adjustment of the turret required in order to compensate for wear of the scouring wheel 42 may be readily ac-
- 15 complished without interfering with the proper rotation of the various vertical shafts. At the loading station the operator will place the leather portion 246 of the heel in an inverted position on the base clamping
- 20 member 140 and will be able readily to locate the same thereon by means of the engagement of the upstanding jig pins 142 with the jig holes 237 formed in the heel seat portion 246 of the heel. He will also
- 25 be able readily to locate the rubber portion of the heel on the leather part because of similar projections 227 and recesses 224 formed thereon in a manner described in my above-mentioned Letters Patent No.
- 30 1,613,096, granted January 4, 1927. Having placed the several parts of the heel between the clamping devices the turret will be caused to move and the upper clamping member 144 will be forcibly pressed against
- 35 the tread surface of the rubber portion of the heel to hold the various parts in proper relation to the turret for presentation to the tools. If desired, a suitable adhesive may be applied to the coacting surfaces of
- 40 the leather and rubber portions before they are positioned in the clamp and the clamping utilized for holding the two parts together during an interval sufficiently long to cause the adhesive to set. As the turret
- 45 rotates through 120 degrees it will bring the heel which has just been positioned by the operator past the heel breasting cutter. If the curvature of the breast of the heel does not coincide with the curvature of the tur-
- 50 ret and hence the curvature of the path of movement of the work a suitable depression or projection on a cam plate 134 will cause a radial movement of the work-holding means against or with the action of the
- 55 springs 126 to correct the path of movement in order to compensate for this difference of curvature. The turret will then halt temporarily under the action of the cam 116, the bell crank 100 and their combined action
- 60 on the worm 86 to cause the turret to dwell for an interval sufficiently long to allow the operator to place a new piece of work between the clamping devices at the front of the machine. The turret will then again ro-

tate through 120 degrees to carry the work 65 past the scouring wheel 42 and it will be remembered that this wheel is not only rotating preferably in a direction opposite to the direction of movement of the turret, but is also being oscillated vertically to ensure 70 even wear of the working face of the scouring tool. At the next intermittent movement of the turret the clamp will be released, the work lifted off the studs 142 by means of the action of the ejector rods 170 when lifted 75 by their coacting cam and the piece of work forcibly ejected from the clamp by the swiping action of the spring 190 mounted on the arm 180. Further movement of the turret brings this carrier to the operator's position. 80

Having described the invention, what I claim as new and desire to secure by Letters Patent of the United States is:—

1. In a machine for operating on blanks, a rotatable work-supporting turret provided with jig pins to receive and position a blank upon the turret, means operable positively by the rotation of the turret to clamp a blank on the turret and to unclamp the blank at a later time, and an ejecting device 85 for lifting the blank off the jig pins comprising means movable with respect to the surface of the turret and stationary means for moving said ejecting device to lift the blank. 90

2. In a machine for operating on blanks, a rotatable work-supporting turret provided with jig pins to receive and position a blank upon the turret, a clamping device 100 movably mounted upon the turret, a clamp-actuating member secured to said clamping device and extending outside the turret, a cam operatively associated with said actuating member for positively actuating said clamping device to clamp a blank on the turret and later to unclamp the blank, an ejecting rod movably mounted on the turret to lift the blank off the jig pins, and a stationary cam surface arranged to coact with said ejecting rod during rotation of the turret 105 to lift the blank from the jig pins after the clamping device has been released. 110

3. In a machine for operating on blanks, a rotatable work-supporting turret provided with jig pins adapted to receive and position a blank with respect to the turret, a clamping device movable toward and away from the turret, means actuated positively by the rotation of the turret to move the clamping device to clamp and later to release the 115 blank, elevating means movably mounted upon the turret for movement under the control of the rotation of the turret to lift a blank off the jig pins, an ejecting member mounted for lateral movement upon the turret adjacent to the clamping device, and stationary means for operating said ejecting member upon rotation of the turret to push 120

- a blank laterally out of the clamping device after it has been lifted by means of the elevating means.
4. In a machine for operating on blanks, a rotatable work-supporting turret provided with jig pins adapted to receive and position a blank with respect to the turret, a clamping device movable toward and away from the turret, means actuated positively by rotation of the turret to move the clamping device to clamp and later to release the blank, a rod movably associated with said clamping device and arranged to contact with a fixed cam surface during the rotation of the turret thereby to lift the blank off the jig pins, a pivoted arm mounted on the turret adjacent to the clamping device, and a fixed cam surface arranged to actuate said pivoted arm upon rotation of the turret to push the blank laterally out of the clamping device after it has been lifted by means of said rod.
5. In a machine for operating on blanks, a conveyor, a work-clamping device carried by said conveyor, relatively fixed means for operating said clamping device positively to clamp a blank, a movably mounted work-ejecting device associated with said work-clamping device, and a relatively fixed cam for operating said ejecting device positively to push a piece of work laterally out of the clamp after the clamp has been loosened.
6. In a machine for operating on blanks, a rotatable work-carrying turret, a work-clamping device carried by said turret, a relatively fixed cam, a plunger coacting with said cam and arranged to actuate said work-clamping device, a pivotally mounted work-ejecting device associated with said work-clamping device and provided with an extension outside said turret, and a relatively fixed cam coacting with said extension to oscillate said ejecting device to push a piece of work laterally out of the clamp after the clamp has been loosened.
7. In a machine for operating on blanks, a conveyor provided with a device for clamping a single blank, means for operating said clamping device, a plurality of movable ejecting devices associated with said clamping device arranged to operate upon said blank when released therefrom, said ejecting devices being mounted on said conveyor, and means for operating said ejecting devices in timed relation to the operation of said clamping device.
8. In a machine for operating on blanks, a conveyor provided with a device for clamping a piece of work, means for operating said clamping device, a sliding ejector rod and a pivotally mounted ejector arm movably mounted upon said turret adjacent to said clamping device, and cam surfaces for operating said ejecting devices in timed relation to the operation of said clamping device.
9. In a machine for operating on blanks, a conveyor provided with a device for clamping a piece of work, means for operating said clamping device, a plurality of movable ejecting devices associated with said clamping device operable upon a single piece of work, and positive means for operating said ejecting devices in timed relation to one another.
10. In a machine for operating on blanks, a conveyor provided with a device for clamping a piece of work, means for operating said clamping device, a plurality of movable ejecting devices associated with said clamping device arranged to eject the piece of work which has been clamped thereby, said ejecting devices being mounted on said conveyor, and means for operating said ejecting devices in timed relation to one another and said clamping device.
11. In a machine for operating on blanks, a rotatable turret, a plurality of work clamping devices carried by said turret, a tool for acting upon pieces of work held in said clamps during rotation of the turret, and means for adjusting the center of rotation of said turret to change the relation of the path of movement of the work clamped thereon with respect to said operating tool to compensate for wear of the latter.
12. In a machine for operating on blanks, a frame, a slide on said frame, a rotatable turret pivotally mounted on said slide, a screw for adjusting said slide in the frame, a plurality of work-clamping devices carried by said turret, means for rotating said turret, a rotatable tool carried in said frame in a position for acting upon pieces of work held in said clamping devices during rotation of the turret, and a screw for adjusting said slide to move the center of rotation of the turret so as to change the relation of the path of movement of the pieces of work clamped on the turret with respect to the rotatable tool.
13. In a machine for operating on blanks, a rotatable turret, a plurality of work clamping devices on said turret whereby pieces of work may be carried in a circular path, a tool adapted to act upon a portion of the periphery of the successive pieces of work held in said clamp, means for rotating said turret to carry a piece of work into engagement with and past the tool, and means for adjusting the position of the center of rotation of the turret with respect to said tool whereby the wearing away of the tool may be compensated for and its effect upon successive pieces of work kept substantially constant.
14. In a machine for operating on blanks, a rotatable work-carrying turret, two tools

- for acting successively upon work carried by said turret spaced apart around the periphery of the turret, and means for adjusting the center of rotation of the turret
- 5 in a direction such that the relation of one of the tools to the paths of movement of successive pieces of work shall remain substantially unchanged and that the wearing away of the other tool may be compensated
- 10 for so that its effect upon successive pieces of work shall remain substantially unchanged.
- 15 16. In a machine for operating on blanks, a rotatable work-carrying turret, a plurality of rotatable tools mounted upon axes substantially perpendicular to the plane of rotation of the turret and disposed a substantial distance apart around the periphery of the turret, and means for adjusting the center of rotation of said turret with respect to
- 20 the axes of said tools in a direction substantially perpendicular to a line joining the center of rotation of the turret and the axis of one of said tools whereby the effective relation of the periphery of the other tool
- 25 with respect to successive pieces of work may be maintained in spite of the wearing away of said latter tool.
17. In a machine for operating on blanks, an operating tool, a rotatable work-carrying turret, a motor for driving said turret to transfer the point of operation of the tool along the work, driving connections comprising only shafts and gears between said motor and said turret, and means for adjusting the center of rotation of the turret with respect to said tool, said driving connections being constructed and arranged to allow said adjustment without disturbing the effective operating relation of the motor
- 40 and the turret.
18. In a machine for operating on blanks, a frame, a slide on said frame, a rotatable work-carrying turret pivotally mounted on said slide and provided with an actuating gear, a pinion in said slide in fixed relation to said gear to drive the same, a motor for driving said turret mounted in said frame, shafts and gears connecting the pinion and the motor, an operating tool mounted in said frame, means for moving said slide to adjust the center of rotation of the turret with respect to said tool, and an Oldham coupling in a shaft between said driving motor and the pinion on said slide constructed and arranged to allow adjustment of the center of rotation of the turret without disturbing the effective connection between the motor and the turret.
- 45 19. In a machine for operating on blanks, a rotatable turret, a driving motor for said turret having a shaft with its axis substantially parallel to the axis of rotation of the turret, means for shifting the axis of rotation of the turret with respect to the
- 50 axis of the shaft of the driving motor, and
- 55 shafts and gears for connecting said shaft to said turret constructed and arranged to rotate the turret undisturbed by the shifting of the axis of rotation of the turret.
- 60 20. In a machine for operating on blanks, an annular work-carrying turret, a plurality of rotatable tools located within said annulus and disposed upon axes substantially parallel to the axis of rotation of the turret, means for rotating said turret to carry successive pieces of work past the periphery of each of said tools, means for rotating each of said tools, and means for imparting axial movement to one of said tools to distribute the wear of the work across the width of the periphery of said tool.
- 65 21. In a machine of the character described, a turret rotatable around a fixed axis, a driving motor having its shaft substantially parallel to the axis of rotation of the turret, and means for connecting said shaft of the driving motor to the turret constructed and arranged to cause the turret to move through predetermined fractions of a rotation and to dwell for a predetermined period intermediate between each of said fractional movements.
- 70 22. In a machine for scouring the breasts of unattached composite heels, a rotatable work-supporting annular turret provided with jig pins to receive and position a heel upon the turret, a clamping device arranged to hold a heel in position upon the jig pins during a partial rotation of the turret, a scouring tool within the annulus of the turret having its operative face in position to act upon the breast of a heel carried past the tool by the turret, and means for releasing the clamp and lifting the heel from the jig pins after it has been treated by said scouring tool.
- 75 23. In a machine for scouring the breasts of unattached heels, a rotatable turret, a device for clamping a heel upon said turret, a scouring tool for acting upon a heel held in said clamping device during rotation of the turret, and means for adjusting the center of rotation of said turret to change the relation of the path of movement of the

heel clamped thereon with respect to said scouring tool to compensate for wear of the latter.

24. In a machine for operating on blanks, a conveyor provided with jig pins to receive and position a blank upon the conveyor, means operable positively by the movement of the conveyor to clamp a blank on the conveyor and later to unclamp the blank,

an ejector for lifting the blank off the jig pins comprising means movable with respect to the path of movement of the conveyor, and stationary means for moving said ejector to lift the blank.

In testimony whereof I have signed my name to this specification.

JOHN B. HADAWAY.
